UNITED STATES PATENT OFFICE

ALBERT C. HOUGLAND, OF ST. PAUL, MINNESOTA

VAT CONSTRUCTION

Application filed August 25, 1930. Serial No. 477,502.

This invention relates to large tanks or vats for liquids and particularly to those having insulating walls and a sheet metal liner subjected to the pressure exerted by the liquid 5 contents.

It is my object to provide a novel and efficient connection for the liner of such a vat at the edges of the walls. A further object is to provide an unusually strong connection between the liner and the outer wall or casing which is easy to construct and presents an unusually neat appearance.

The invention will be best understood by reference to the accompanying drawing in which Figure 1 is an end view of a large vat, such as is employed in cream ripeners and pasteurizers, with a portion of one of the ends broken away to show my improved connection between the liner and casing; Fig. 2 is an isometric view showing fragmentary portions of the several elements in their relative positions before the locking connection is made; Fig. 3 is an isometric view showing the lock connection partially completed and Fig. 25 4 is a similar view showing the completed lock.

As shown in the drawing a large vat 5 has thick insulating walls containing a body 6 of insulating material such as cork. This cork insulation is confined by an outer casing 7 of heavy gauge sheet metal which extends over the edges 8 of the walls and downward within the vat to provide a locking flange 9 for confining the body 6.

Overlapping the casing along the edge 8 is a long and relatively narrow strip 10 of relatively light gauge metal. This strip has a flange 11 along its outer edge which, when the strip is applied, projects outward from the casing 7. The strip 10 is overlapped by a relatively heavy bar 12 and this bar is held in place by a series of screws 13 extending through the strip 10 and having a threaded engagement with the casing 7. The flange 11 is preferably offset upward, as clearly indicated in Fig. 2, to extend substantially in the plane of the upper surface of the bar 12.

A liner sheet 14 is suspended from its upper edge on the bar 12, being bent outward to overlap said bar. During the construction of

the vat, when the liner is first inserted, its outer margin projects beyond the flange 11, as indicated in Fig. 2, to form a flange 15 adapted to interlock with the flange 11. By a swaging operation the flange 15 is bent 55 downward and inward to embrace the outer edge of the flange 11 (as shown in Fig. 3) and then both flanges are folded downward to their final positions, shown in Figs. 1 and 4.

The body 6 of cork compresses under the 60 pressure of the contents so that considerable tension is placed on the liner 14 and this tension is transmitted to the edges of the vat and locking connection between the strip, flange 11 and the liner flange 15. It will now 65 be understood that a strong locking engagement between the liner and outer casing is produced and the edge construction is adapted to withstand the forces exerted by the liquid contents of the vat. The vat presents an 70 unusually neat appearance as no fastenings are visible around its edges and smooth bearings are afforded for the cover 16.

My invention has the further advantage of 75 making it possible to employ a strong wall construction in which the load carrying edges are channel shaped with deep flanges extending inside of the vat. A large part of the weight of the contents of the vat is transmitted to such rigid channel members by my 80 arrangement, and an edge of the main load carrying member or outer casing sheet is not required for the connection with the other members.

My invention has been employed to advantage in the construction of cream ripeners and pasteurizers of five hundred gallon capacity or larger but it will be understood that it may be used in tanks, vats or containers for numerous other purposes without departing from 85 the spirit of my invention.

Having described my invention what I claim as new and desire to protect by Letters Patent is:

1. In a vat having a wall, a narrow and relatively long strip of sheet metal extending along an edge of said wall and having a foldable flange adapted to project therefrom, means for securing said strip to said edge, a linear sheet extending from the interior of 95 100

the vat across said edge and overlapping said strip and having a foldable flange adapted to project beyond the flange on said strip and a lock joint formed by bending said flanges together.

5 2. In a vat having a wall, a strip of sheet metal extending along an edge of said wall and having a foldable flange adapted to project therefrom, means for securing said strip to said edge, a liner sheet extending from the interior of the vat across said edge and overlapping said strip and having a foldable flange adapted to project beyond the flange on said strip and a lock joint formed by the 10 flange on said liner bent to embrace said flange on said strip and both flanges being bent to extend substantially parallel to the outer surface of said wall.

15 3. In a vat having a wall, a strip of sheet metal extending along an edge of said wall and having a foldable flange adapted to project therefrom, a bar secured in overlapping relation to said strip, means for securing said bar to said edge, a liner sheet overlapping said bar and having a foldable flange adapted to 20 project beyond the flange on said strip and a lock joint formed by bending the flange on said liner to embrace said flange on said strip and both flanges being to extend substantially parallel to the outer surface of said wall.

25 4. In a vat a wall containing a body of insulated material, a sheet metal casing extending upon the outer surface of said body and along an edge thereof, a strip of sheet metal secured to said casing along said edge, a relatively heavy bar overlapping said strip along said edge, a liner sheet extending from the interior of the vat outward over said bar and interlocking flanges along the overlapped 30 edges of said strip and liner.

35 5. In a vat a wall containing a thick body of insulated material, a sheet metal casing extending upon the outer surface of said body, along an edge thereof, a flange on the edge of said casing extending within the vat to embrace said body of insulating material, a strip of sheet metal secured to said casing along said edge, a relatively heavy bar overlapping 40 said strip along said edge, a liner sheet extending from the interior of the vat outward over said bar and interlocking flanges formed on the outer edges of said strip and liner.

45 6. In a vat the combination with a wall containing a thick body of compressible insulated material, of a sheet metal casing extending upon the outer surface of said body and along an edge thereof, a strip of sheet metal secured to said casing along said edge, a 50 bar overlapping said strip along said edge, a liner sheet supported within the vat on said body of insulating material and extending from the interior of the vat outward over said bar and interlocking flanges formed on the 55 outer edges of said strip and liner.

7. In a vat the combination with a wall having a heavy sheet metal casing extending inside of the vat, of a narrow and relatively long strip of sheet metal extending along an edge of said wall and having a foldable flange adapted to project from the outer surface of said vat, means for securing said strip to said edge, a liner sheet extending from the interior of the vat across said edge and overlapping said strip and having a foldable flange adapted to project beyond the flange on said strip and a lock joint formed by bending said flanges together.

70 8. In a vat the combination with a wall having a channel-shaped edge member for supporting at least a part of the weight of the contents, said member having portions extending from the edge over the inner and outer surfaces of the wall, of a strip of sheet metal secured to said member and extending 75 therealong, a relatively heavy bar overlapping said strip along said edge, a liner sheet extending from the interior of the vat outward over said bar and interlocking flanges along the overlapped edges of said strip and liner.

75 In testimony whereof, I have hereunto signed my name to this specification.

ALBERT C. HOUGLAND.
